Primary Examiner — Khawaja Anwar*Assistant Examiner* — Taylor O Mortorff(74) Attorney, Agent, or Firm — WARNER NORCROSS + JUDD LLP(57) CLAIM

The ornamental design for a handle for a floor cleaner, as shown and described.

DESCRIPTION

FIG. 1 is a front perspective view of a handle for a floor cleaner showing our new design;

FIG. 2 is rear perspective view thereof;

FIG. 3 a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The details of the handle for a floor cleaner shown in broken lines form no part of the claimed design.

1 Claim, 3 Drawing Sheets
